Claims priority, application Great Britain Mar. 18, 1960
 8 Claims. (Cl. 122—510)

The present invention relates to forced-flow steam generators and particularly to the combustion chamber structure thereof.

It is an object of the invention to provide in a forced-flow steam generator a furnace whose walls are formed by tangent serpentine tubes and yieldable under changing temperature conditions.

Difficulties were encountered with combustion chamber linings of the aforescribed type, particularly if the combustion chamber casing and its insulation are supported by the tubes.

According to the invention the tubular furnace walls of a forced-flow steam generator are carried by substantially vertical support tubes serving as feeder tubes and arranged at the corners of the furnace, each furnace wall comprising a series of serpentine tubes to which operating fluid is supplied by said feeder tubes. The feeder tubes are hung on a supporting framework and the tubes forming the side walls of the furnace are connected to supporting frames composed of bars and plates, said frames being partly rigidly and partly slidably connected to tubes forming the furnace wall as well as to the vertical support tubes to afford expansion and contraction under varying temperature conditions.

The novel features which are considered characteristic of the invention are set forth with particularity in the appended claims. The invention itself, however, and additional objects and advantages thereof will best be understood from the following description of embodiments thereof when read in connection with the accompanying drawing wherein:

FIG. 1 is a diagrammatic rear view of a combustion chamber wall according to the invention with parts broken off or removed and showing only one supporting frame.

FIG. 2 is a horizontal sectional view of tubes near a corner of a combustion chamber one wall whereof is shown in FIG. 1; the section is made along line A—B of FIG. 1.

FIG. 3 is a vertical sectional view of a support frame with combustion chamber wall tubes connected thereto, the section being made along line C—D of FIG. 1.

FIG. 4 is a vertical sectional view of a support frame showing its connection to a vertical corner tube, the section being made along line E—F of FIG. 1.

FIG. 5 is an elevation of a portion of a group of tubes in the neighborhood of a rectangular bend at the transition from the vertical support tubes to the horizontal wall-forming tubes.

FIG. 6 is a horizontal sectional view taken along line G—H of FIG. 1, of one of the four corners of a rectangular combustion chamber. The other corners, not shown, are constructed in the same manner as the illustrated corner.

In the illustrated example an evaporating tube section 1 is provided on each wall of a combustion chamber whose horizontal section is substantially rectangular. Only one wall formed by one evaporating tube section and four vertical tubes of a second evaporating section are shown in FIG. 1. Each tube section is formed by a group of seven juxtaposed tubes, four of the tubes being numbered 2, 3, 4, 5. The tubes have horizontal portions forming panels, the tubes of one panel being connected by vertical or hairpin-like portions to the tubes of the

2

preceding and of the subsequent panels. The tubes are continuous and extend in serpentine fashion from the bottom end to the top end of the respective wall. Substantially vertical, laterally tangent tubes are placed at the four corners of the furnace and form groups of seven tubes at each corner. In the illustrated example the diameter of the vertical tubes is greater than that of the wall forming serpentine tubes. The vertical tubes at the right corner and visible in FIG. 1 are numbered 9, 8, 7, 6, three more tubes being placed behind the tube 6. The tubes at the left corner and visible in FIG. 1 are numbered 13, 12, 11, 6, three more tubes being behind tube 6. The tubes of each group of vertical corner tubes are individually connected to the tubes forming one wall of the furnace and serve to feed operating medium into the wall tubes. The vertical tubes depend from a supporting framework or structure 34 and serve as supports for frames to which the tubes forming the furnace walls are connected. To stabilize the relative position of the neighboring marginal tubes of the tubular wall panels groove-and-tongue joints 14, 15 are provided as shown in FIG. 3. Similar joints 16, 17 are provided between the vertical marginal tube portions of the wall panels and the neighboring vertical corner tubes as shown in FIG. 2.

25 The weight of the tubular wall panels is transferred to the respective vertical corner tubes by a framework including horizontal channels or U-beams 21 and 26 extending across the furnace walls. The horizontal tubes 2, 3, 4, 5 of each panel are welded to vertical rods 18 for fixing the tubes in vertical planes. In order to permit relative expansion of neighboring tubes the welds are arranged in staggered or offset relation, preferably two tubes being left unwelded between two welded tubes. An upper lug 19 and a lower lug 20 are welded to every fourth rod 18. The lower channels 21 are supported by brackets 22 (FIG. 4) welded to the corner tubes. The channels 21 are provided with vertical webs 23 parallel and corresponding to the lugs 20 which extend through suitable apertures in the web of the channel 21. The adjacent lugs 20 and webs 23 are connected by pins 24 connected to the lugs and extending through vertical slots 25 in the webs 23 to permit relative vertical movement of the lugs and webs. This construction also permits relative horizontal movement of the lugs and webs.

30 45 In order to make the channels 21 more rigid the channels 26, which are placed above and spaced from the channels 21, are connected to the channels 21 by vertical T-irons or uprights 27. In addition, flat steel plates 28 are welded to and interconnect the channels and fill the spaces between the channels and the uprights 27. Bolts 30 mounted on the lugs 19 and extending loosely through bores in spaced webs welded to the channels 26, and placed normal to the lugs and webs transfer the weight of the panels to the channels 26 and permit relative horizontal movement. The upper channels 26 are connected to the respective vertical corner tubes by sliding points each joint comprising a lug 31 and a pin 33 connected thereto, the pin extending through vertical slots 31' in the opposed end faces of the elements 26. These joints are similar to the joints 24, 25 to permit relative vertical movement of the upper channels and the respective corner tubes.

As seen in FIG. 5, short aligning bars 32 are alternately 65 welded in offset relation to the tubes forming the wall panels in the neighborhood of the bends between the horizontal portions of the tubes and the vertical corner tubes. The bars 32 slidably engage the respective neighboring tubes to fix the tubes in a plane while permitting relative longitudinal expansion of the tubes.

Refractory sealing material 36 is applied to the back side of the tube panels and is about as thick as the rods 18

in order to prevent escape of combustion gas. Casing plates 35 are welded to the support frames in back of the refractory material and form, together with the plates of the support frames, a gastight skin provided with expansion joints and reinforcements in the conventional manner. Outside the skin casing is an outer casing containing insulating material for the boiler walls.

Horizontal strap elements are connected to the upper and lower channels and extend from corner to corner of the furnace. The ends of these elements are connected at the corners of the furnace to counteract horizontal pressure caused by explosions within the combustion chamber. These strap elements are connected to the casing and to one another by bolt joints permitting relative movement in certain directions in a manner similar to that adopted in known designs of skin casing for other than forced-flow steam generators.

The support frames and the skin have, due to the outer insulation, substantially the same temperature as the fluid in the tubes and expand with the tubes. In operation, the fluid temperature in the panel coils increases progressively and continuously from bottom to top of the steam generator. Therefore, the upper portions of the structure expand more than the lower. The corner tubes have a lower temperature than the tubes of the wall panels because the operating fluid enters the top end of the corner tubes. These temperature differences are rendered harmless by the sliding overlapping fin joints between the outer tubes of each panel and the adjacent vertical corner tubes.

While a specific embodiment of the invention has been shown and described, it will be apparent to those skilled in the art that various changes, modifications, substitutions, additions and omissions may be made therein without departing from the spirit and scope of the invention as set forth in the appended claims.

I claim:

1. In a forced-flow steam generator comprising a combustion chamber of angular horizontal cross section and having a plurality of side walls and corners therebetween, a supporting framework, substantially vertical tubes placed in each corner of said combustion chamber and hung on said framework, a plurality of said vertical tubes being placed in the plane of one of the side walls extending from the corner and a plurality of said vertical tubes being placed in the plane of the second side wall extending from said corner:

tubes bent in serpentine fashion placed in planes and forming tube panels forming the parts of said side walls between said vertical tubes,

at least one horizontal support frame for each side wall, each of said support frames comprising a horizontal structural steel element at the upper end of the frame, a horizontal structural steel element at the lower end of the frame, and a steel plate placed between said structural steel elements.

support brackets connected to said vertical tubes outside of the combustion chamber for supporting one of said structural steel elements,

sliding connections vertically slidably connecting the second of said structural steel elements to said vertical tubes,

vertically slidable connections between said tube panels and one of said structural steel elements, and horizontally slidable connections between said tube panels and the second of said structural steel elements.

2. In a forced-flow steam generator as defined in claim 1 and wherein the lower of said structural steel elements rests on said support brackets.

3. In a forced-flow steam generator as defined in claim 1 and wherein said sliding connections vertically slidably connect the upper of said structural steel elements to said vertical tubes, said vertically slidable connections are arranged between the lower of said structural steel ele-

ments and said tube panels, and said horizontally slidable connections are arranged between the upper of said structural steel elements and said panels.

4. In a forced-flow steam generator comprising a combustion chamber of angular horizontal cross section and having a plurality of side walls and corners therebetween, a supporting framework, a plurality of substantially vertical tubes placed in each corner of said combustion chamber and hung on said framework, each of said side walls being formed by a plurality of tubes bent in serpentine fashion and placed in a plane, said wall-forming tubes being connected to said vertical tubes to receive operating medium therefrom, at least one support frame for each side wall, each of said support frames being composed of structural steel elements and steel plates, support brackets connected to said vertical tubes outside of the combustion chamber, said support frames resting on said brackets, sliding connections slidably connecting said support frames to said vertical tubes and to said wall-forming tubes, one of said support brackets and a lug being welded in axially spaced relation to at least one of said vertical tubes in each corner, a web connected to the support frame supported by said bracket, said lug and said web being placed side by side and in parallel relation, said web having a vertically slotted hole, and a bolt connected to said lug and extending through said slotted holes for holding said support frame to said vertical tube and permitting relative movement of said lug and said web.

5. In a forced-flow steam generator comprising a combustion chamber of angular horizontal cross section and having a plurality of side walls and corners therebetween, a supporting framework, a plurality of substantially vertical tubes placed in each corner of said combustion chamber and hung on said framework, each of said side walls being formed by a plurality of tubes bent in serpentine fashion and placed in a plane, said wall-forming tubes being connected to said vertical tubes to receive operating medium therefrom, at least one support frame for each side wall, each of said support frames being composed of structural steel elements and steel plates, support brackets connected to said vertical tubes outside of the combustion chamber, said support frames resting on said brackets, and sliding connections slidably connecting said support frames to said vertical tubes and to said wall-forming tubes, each of said support frames including a lower horizontal channel, an upper horizontal channel spaced from said lower channel, and vertical elements interconnecting said channels, said lower channel resting on said support brackets and being vertically movably connected to said wall-forming tubes, said upper channel being vertically movably connected to said vertical tubes and being vertically unmovably connected to said wall-forming tubes.

6. In a forced-flow steam generator as defined in claim 1 and wherein each of said structural steel elements is formed by a channel, uprights being provided interconnecting said channels, and said plates being placed parallel to and filling the spaces between said uprights and said channels.

7. In a forced-flow steam generator as defined in claim 1 and wherein each of said vertical tubes is connected to one of said tubes bent in serpentine fashion for supplying operating medium thereto.

8. In a forced-flow steam generator as defined in claim 1 and wherein the diameter of said vertical tubes is greater than that of said tubes bent in serpentine fashion.
